[57] CLAIM

The ornamental design for roller buoy for storing rope connected to an underwater article, as shown and described.

DESCRIPTION

FIG. 1 is a side elevational view of a roller buoy for storing rope connected to an underwater article showing our new design; and a view of the side opposite being substantially a mirror image;

FIG. 2 is front elevational view thereof, the rear elevational view thereof being substantially a mirror image; and

FIGS. 3 and 4 are respectively top and bottom plan views.

FIG. 1

FIG. 2

FIG. 3

FIG. 4
